UNITED STATES PATENT OFFICE.

CHARLES S. BATDORF, OF BROOKLYN, NEW YORK, ASSIGNOR TO AUTOMATIC COIN-WRAPPING MACHINE COMPANY, OF NEW YORK, N. Y., A CORPORATION OF NEW YORK.

MOVABLE FEED-ROLL CARRIER.

1,168,780.

Specification of Letters Patent.

Patented Jan. 18, 1916.

Application filed April 11, 1910. Serial No. 554,643.

To all whom it may concern:

Be it known that I, CHARLES S. BATDORF, a citizen of the United States, residing at Brooklyn, county of Kings, State of New York, have invented certain new and useful Improvements in Movable Feed-Roll Carriers, of which the following is a full, clear, and exact description.

My invention relates to wrapper feeding mechanism for article wrapping machines, such for example, as that illustrated in my Patent No. 998,830 granted July 25, 1911, the object of the invention being to provide an improved construction and arrangement of feeding rolls, including means of mounting the presser roll, whereby the wrapper strip may be fed when the presser roll is in one position and whereby the presser roll may be readily moved free of the co-operating roll, to facilitate the threading or removal of the strip.

A further object of the invention is to provide improved means for straightening the wrapper strip or taking out the curl due to the fact that the wrapper supply is usually conveniently arranged in a roll, such rolling of the strip necessarily results in causing the same to curl when freed from the roll.

With these objects in view, the invention consists in the construction and arrangements of parts, a preferred embodiment of which is illustrated in the accompanying drawings, in which,—

Figure 1 is a plan view of so much of a coin wrapping machine, showing the invention in conjunction therewith as is necessary to illustrate the same. Fig. 2 is a side elevation of the parts shown in Fig. 1. Fig. 3 is a detail view of an eccentric hub and operating arm therewith, in which the shaft of the presser roll is operably mounted. Fig. 4 is an edge view of the part shown in Fig. 3. Fig. 5 is a detail view showing the manner of mounting the opposite end of the presser roll shaft. Fig. 6 is a view of the parts shown in Fig. 5, looking from the right. Fig. 7 is a sectional view on the line 7—7, Fig. 1 of the wrapper strip straightening device.

In the drawings, 1—1 indicates fragmentary parts of the side frames of the machine.

2 indicates a frame member upon which the wrapper roll support 3 is adjustably mounted by means of a set screw 4, whereby said roll support may be adjusted to align properly with the feed rolls. Rotatably mounted in open bearings in arms 5—5, extending forwardly from the wrapper roll support is a wrapper straightening device, comprising a transverse bar 6, preferably constructed with a flat upper surface 7, Fig. 7 presenting abrupt corners 8—9 to the passage of the wrapper strip 10 thereover. On the straightening bar 6 is mounted a presser plate 11 secured to said bar by means of the bolts 12 and nuts 13, which bolts extend through to the opposite side of the bar 6 and their lower ends are connected by a transverse bar 14 secured thereto by the nuts 15. Surrounding the bolts 12 and between the straightening bar and the bar 14 are springs 16 which serve to hold the presser bar 11 with more or less pressure against the straightening bar 6, thereby causing the wrapper strip to be held firmly against said straightening bar. The straightener bar 6 together with the parts carried thereby is held in adjusted position by means of spring plates 6' secured to the arms 5 by screws 5', the ends of said plates being pressed heavily against the extremities of said bar 6 opposite the open bearings respectively in the arms 5 whereby the bar 6 is held stationary against the drag of the strip thereon. With the straightening bar in the position indicated in Fig. 2, comparatively little straightening effect is produced upon the wrapper strip. If however, the upper side of the straightening bar be tilted toward the wrapper roll, the outer edge 9 of the said bar in conjunction with the presser bar 11, which serves to hold the strip firmly against the upper side of the straightening bar, serves to straighten the strip by removing the curl thereof due to its previously rolled condition. The straightening bar is provided with a knurled head 17, by which said bar may be manually tilted to any desired position determined by the amount of curl of the strip and by the stiffness of the material thereof. It is evident that as the supply roll is reduced in diameter by reason of the feeding of the wrapper strip, the curl of the strip will be-

come more pronounced. It will therefore, be necessary to tilt the straightening bar to a greater degree toward said supply roll, in order to straighten said strip as the supply roll is reduced.

5 In the side frame 1 is journaled a feed roll shaft 18 carrying the main feed roll 19, and mounted adjacent said roll 19 is a presser roll 20 carried by the shaft 21. The lower 10 end of the shaft 21 as viewed in Fig. 1 is mounted in an eccentric aperture 22 of an eccentric hub 23 journaled in the side frame 1, said hub having a manually operable arm 24, whereby said shaft may be shifted to 15 carry the presser roll into and out of engagement with the feed roll 19. The opposite end of the shaft 21 is mounted by a universal joint 25 in the hub 26 of the pinion 27, said hub 26 being journaled in the adjacent 20 side frame 1. The pinion 27 is engaged by gear 28 which in turn may be connected with any suitable form of rack arm as illustrated in my patent above referred to, whereby said feed roll 19 and the presser 25 roll 20 may be actuated to feed the strip. To draw the presser roll 20 firmly against the feed roll 19 suitable springs 29 are interposed between the shafts 18 and 21 carrying said rolls respectively. On the side 30 frame 1 adjacent the eccentric operating arm 24 is an adjustable stop pin 24^a by which the degree of pressure exerted by the presser roll 20 upon the strip fed over the roll 19 may be regulated according to the 35 thickness of the strip and the degree of pressure required to properly feed the same between said rolls.

In Fig. 2 is illustrated a guide plate 30 and a knife 31, said parts being mounted 40 upon an arm 32 supported on the machine frame and by which the wrapper strip may be guided to the wrapping mechanism and may be severed when a sufficient amount has been fed to form a wrapper of required 45 length.

While I have herein illustrated the preferred embodiment of my invention, it is understood that the same may be altered in detail and relative arrangement of parts 50 within the scope of the appended claims.

What I claim is:

1. In a wrapper feeding mechanism, the combination with a wrapper supply of a feed roll and presser roll coöperating therewith, a shaft for said presser roll a rotatable support for one end of said shaft, a universal joint between said support and said shaft, a rotatable support for the opposite end of said shaft, upon which said shaft is eccentrically mounted and means for rotating the latter support to move said presser roll into and out of engagement with said feed roll.

2. In a wrapper feeding mechanism, the combination with a wrapper supply of a

70 feed roll and a presser roll coöperating therewith, a shaft for said presser roll, a rotatable support for one end of said shaft, a universal joint connecting said support and shaft, a pinion on said support, a gear fixed to said feed roll and meshing with said pinion, means for operating said gear to rotate said feed roll and presser roll respectively, a rotatable support for the opposite end of said presser roll in which said shaft is eccentrically mounted, and manually operable means for rotating said latter support to move said presser roll into and out of engagement with said feed roll.

3. In a wrapper feeding mechanism, the combination with a wrapper supply of a feed roll and a presser roll coöperating therewith, a shaft for said presser roll, a rotatable support for said shaft in which one end of the latter is eccentrically mounted, 85 means for rotating said support to move said presser roll into and out of engagement with said feed roll, and an adjustable stop in the path of said rotating means to determine the degree of pressure of said presser 90 roll on said feed roll.

4. In a wrapper feeding mechanism, the combination with a wrapper supply of a feed roll and a presser roll coöperating therewith, a shaft for said presser roll, a rotatable support for one end only of said shaft in which said shaft is eccentrically mounted, means for rotating said support to move said presser roll into and out of engagement with said feed roll and means 100 for holding said presser roll yieldingly in engagement with said feed roll.

5. In a wrapper feeding mechanism for wrapper rolls, the combination with a wrapper roll support and feeding devices, 105 of a wrapper straightening mechanism comprising an angularly adjustable bar angular in cross section and interposed between said support and said device in such a manner as to deflect the line of feed of the 110 wrapper strip between said support and said device.

6. In a wrapper feeding mechanism for wrapper rolls, the combination with a wrapper roll support and feeding devices, of 115 a wrapper straightening bar angular in cross section mounted transversely of the path of the wrapper strip and arranged to deflect the line of feed of the strip, and means for manually tilting said bar in the line of 120 feed to vary the straightening effect.

7. In a wrapper feeding mechanism for wrapper rolls, the combination with a wrapper roll support, and feeding devices, of an angularly adjustable wrapper straightening 125 bar in the line of feed mounted transversely of the path of the wrapper strip and arranged to deflect the line of feed of the strip between said support and said devices and a presser bar arranged to overlie the 130

wrapper strip in its travel over said straightening bar to assist in the straightening operation.

8. In a wrapper feeding mechanism for 5 wrapper rolls, the combination with a wrapper roll support and a pair of feed rolls, a straightening bar of angular cross section adjustably mounted between said support and said feed rolls, and arranged to cause 10 the wrapper to be deflected from the line of

feed between the support and feed rolls by one of its angles and means for tilting said straightening bar to the path of the wrapper strip and in the line of feed to vary the straightening effect.

CHARLES S. BATDORF.
